UNITED STATES PATENT OFFICE.

ANDREW DUDAS AND ALBERT P. WASIL, OF HOMESTEAD, PENNSYLVANIA.

SAFETY PIN WITH BAYONET POINT.

Application filed August 28, 1926. Serial No. 132,297.

This invention relates to safety-pins and more particularly to improvements in the construction of safety-pins of the so-called Clinton-type.

The primary object of this invention is to provide a safety-pin of the Clinton-type which is able to withstand a much greater pull than ordinary safety-pins of the same size, without causing the opening of said pin. Another object of this invention is to provide a safety-pin in which the pin-bar, after having been considerably deformed owing to the pull exerted thereon will practically lock itself with the cap of said safety-pin and thus prevent the opening thereof. A further object of this invention is to provide a safety-pin which to a great extent prevents the pricking of the flesh of the person on whom the safety-pin is applied. Still another object is the provision of a safety-pin in which the above mentioned features are obtained without adding any special parts to the construction of a Clinton-type pin. Additional features and advantages of this invention will appear in the course of the following description considered in connection with the accompanying drawing forming a part of this application.

In the drawing:

Fig. 1 is a side elevation of one type of safety-pin constructed according to our invention.

Fig. 2 is a similar view of a slightly modified safety-pin.

Fig. 3 is a side elevation of a safety-pin similar to the one shown in Fig. 2 but provided with a combined spring-loop and guard, also of our invention and which forms the subject matter of a co-pending application.

Fig. 4 is a top plan view of the safety-pin-cap used in the safety-pins illustrated in Figs. 2 and 3.

Figs. 5 and 6 are considerably enlarged fractional views showing respectively the conditions of the piercing end of the pin-bar under normal use and when subjected to an excessive pull capable of bending said pin-bar as well as the bridge-bar of the safety-pin of the design shown in Fig. 1.

Figs. 7 and 8 are similar illustrations showing the behavior of the type of safety-pin shown in Figs. 2 and 3 under analogous conditions.

Fig. 9 is a view showing the condition

prevailing when the piercing end of the pin-bar is pushed through cloth, etc.

Referring to the drawing, it will be noted that our improved safety-pins follow in the main the construction of the universally used type of safety-pin known in the art as Clinton-type safety-pin. This pin comprises a bridge-bar 1, a pin-bar 2, the connecting spring-loop 3 and the safety-pin-cap 4. The latter is held securely on the safety-pin by providing on the bridge-bar an upward bend 5 upon which the cap is pressed by means of automatic presses. This cap is, of course, intended to receive and hold therein the pointed end of the pin-bar, when the safety-pin is closed.

In the ordinary Clinton safety-pin, the pin-bar is substantially straight from the spring-loop 3 to the pointed end. We have found after extensive experimentation and modifications that by giving to the pointed end of the pin-bar the substantially bayonet-shaped form shown in the various figures that the resistance of a closed safety-pin against pull is greatly increased while at the same time the insertion of said pin in cloth is not only facilitated but rendered much safer in so far as the danger of pricking a person's flesh is concerned.

As shown in the various figures, the bayonet-shaped pointed end of the pin-bar is formed by first bending up a portion of the pin-bar adjacent the end thereof at an acute angle with the axis of the pin-bar to form the heel portion 6 and by then producing at the end of said heel the downwardly directed piercing element 7 which is preferably bent at such an angle as to bring the point 8 substantially in alignment with the axis of the pin-bar. The piercing element and the heel portion are respectively connected together and to the body proper of the pin-bar by smooth bends or curves 9 and 10 in order to facilitate the insertion or extraction of the pin-bar in or out of cloth.

In the construction shown in Figs. 2, 7 and 8, the ordinary Clinton safety-pin has further been modified by providing in the top portion of the cap 4 the elongated and substantially triangular aperture 11 disposed in axial alignment with the pin-bar and through which a portion of the bayonet-point may protrude for the purpose of establishing a practically positive locking engagement of said bayonet-point with the cap, whereby any accidental opening of the

safety-pin, due to excessive pulling, is prevented as long as the cap maintains its proper shape.

Under normal conditions, the piercing element 7 of a safety-pin constructed in the manner shown in Fig. 1 will assume the position illustrated in Fig. 5, that is, the upper bend 9 will bear against the underside of the top portion of the cap 4 and the heel 6 as well as the piercing element 7 will be at an angle with said underside.

When subjected to an excessive pull, the pin-bar and the bridge-bar will be bent in the manner suggested in Fig. 6. As shown therein, after a certain degree of curvature has been reached in the pin-bar, the straight heel portion 6 will bear completely against the underside of the top portion of the cap and, when in this position, will greatly increase the resistance of the pin-bar against further bending, as proved by actual and prolonged use.

This resistance against bending of the pin-bar is still more augmented when the safety-pin is provided with a notched cap, as depicted in the modified construction. In this case, further bending of the pin-bar will be resisted by the combined action of the flat heel bearing against the underside of the top portion of the cap assisted by the practically positive locking action produced by the engagement of the base portion of the bend 9 with the straight side 12 of the notch or aperture 11. When so constructed, the disengagement of the pin-bar from the cap is practically impossible, unless the safety-pin be so stressed as to cause the spreading of the cap proper.

In Fig. 3 we have shown a safety-pin, which in addition of the above described features is provided with a spring-loop-guard formed integrally with the loop to prevent the pinching of cloth between the turns of said loop, as fully explained in a co-pending application.

We have endeavored to graphically illustrate in Fig. 9 the reason why a bayonet-pointed safety-pin of our invention offers greater protection against pricking of the flesh of a person than the ordinary safety-pin having a straight pin-bar. From this illustration it will be seen that when a pin-bar is pushed through cloth in the usual manner, i. e. substantially parallel to the flesh of a person, the bent portion 9 will be the first one to come in contact with the flesh and that the tendency of the piercing element 7 will be to direct the point 8 outwardly and away from the flesh.

From the above description it will be apparent that we have provided safety-pins which offer the advantages set forth without adding practically to the cost of manufacture of the common type of Clinton safe-

ty-pin by means of automatic machinery 65 made especially for the purpose and readily available in the market.

From the above description taken in connection with the drawing, it is thought that a clear and comprehensive understanding of 70 the construction, operation and advantages of our invention may be had, and while we have shown and described our invention as embodying specific structures, we desire to reserve the right of making such changes in 75 said structures as do not depart from the spirit and scope of the invention as defined in the appended claims.

We claim:

1. In a safety-pin of the character described, a pin-bar having a bayonet-shaped end comprising a heel-portion and a piercing element connected together by a bend, and a cap having an aperture adapted to be engaged by said bend. 80
2. In a safety-pin of the character described, a pin-bar having a bayonet-shaped end comprising a heel-portion and a piercing element connected together by a gradual bend and a cap having a triangular aperture disposed in axial relation with said pin-bar and adapted to be engaged by said bend. 90
3. In a safety-pin, a pin-bar; a bridge-bar and a cap; said pin-bar having a bayonet-shaped end comprising a heel-portion directed outwardly at an acute angle with the axis of said pin-bar and a piercing element disposed at such an acute angle with said heel-portion as to bring the point only of 100 the piercing element substantially in line with the axis of said pin-bar. 95
4. In a safety-pin, a pin-bar; a bridge-bar and a cap, said pin-bar having a bayonet-shaped end disposed in a plane passing 105 substantially through the longitudinal axes of said pin-bar and said bridge-bar and comprising a heel-portion directed outwardly at an acute angle to the axis of said pin-bar and a piercing element disposed at such an acute angle with said heel-portion as to bring the point of the piercing element substantially in line with the axis of said pin-bar; said heel-portion and piercing being 110 respectively connected to said pin-bar and together by gradual bends to facilitate the insertion and extraction of said pin-bar; said cap being adapted to contact only with the gradual bend connecting the piercing element with the heel-portion when the 115 closed pin-bar is under normal load and to contact with said heel portion when the pin-bar is flexed by excessive stresses. 120

In testimony whereof we affix our signatures.

ANDREW DUDAS.
